UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE

FURNACE CONSTRUCTION

Application filed April 6, 1922. Serial No. 549,973.

This invention relates to a new and improved furnace construction and more particularly to the construction of the ports and passages of open hearth furnaces.

As is well known in the art, open hearth furnaces are double-ended and are periodically reversed in their operation so that the ports in each end serve alternately to introduce the incoming air and fuel and to carry away the products of combustion. Since the products of combustion largely exceed in volume the incoming air and gas, the design of the ports and passages is largely dependent upon the requirement that they be adapted to carry away the products of combustion. It is essential for proper furnace operation that the incoming air and fuel be so directed as to properly combine to form a relatively short, hot flame. It is further necessary that this flame should be so directed as to properly heat the bath of metal in the furnace chamber. These two differing requirements for the design of the ports and passages have rendered it impossible to design ports which are fully adapted for both purposes.

In the endeavor to obviate these difficulties, certain furnaces have been designed having supplemental passages for the carrying away of the products of combustion, these passages having no function upon the incoming end of the furnace. Such a furnace is shown in the patent to McKune, No. 1,339,855, issued May 11, 1920.

In all furnaces, difficulties are encountered in preserving the contour of the incoming fuel port due to the fact that the products of combustion passing through said port at high temperature tend to erode its walls. It has been general practice to insert water-cooled members in such ports, these members tending to preserve the outline. Some ports of this type are tubular in form and the entire port consists of a tubular water-cooled member. With such ports, the loss of heat on the outgoing end due to the cooling effect is large and a considerable amount of water is required to keep the port adequately cooled. Therefore, the provision in connection with such ports, of supple-

mental passages for carrying off the products of combustion or the greater portion thereof, is of particular importance.

It is an object of the present invention to provide a furnace construction in which are provided air uptakes located near the gas port and air ports leading from the uptakes adjacent the gas port. 55

It is a further object to provide a construction of this character in which supplemental passages are provided for the products of combustion, such passages in the preferable form leading to the air uptakes. 60

It is also an object to provide a furnace of this general character having a tubular fuel port, and air ports located adjacent the gas port and adapted to deliver an air stream encircling the gas stream. 65

It is an additional object to provide in combination with such air and gas ports and passages, a mixing port located between the air and gas ports and the furnace proper. 70

Other and further objects will appear as the description proceeds.

I have illustrated a preferred embodiment 75 of my invention in the accompanying drawings, in which:

Figure 1 is a longitudinal section showing one end of a furnace constructed according to the present invention; and 80

Figure 2 is a horizontal section taken on line 2-2 of Figure 1.

In the furnace as shown, the fuel uptake 6 leads from the slag pocket 7 to the port 8. This port as shown is a hollow tubular member adapted to be water-cooled by water introduced through pipe 9 and carried away through pipe 10. The port member 8 is held in place in an opening extending through the rear wall 11 of the furnace and connecting the fuel uptake with the mixing port 12. This port 12 leads to the furnace chamber 13 and is defined by piers 14. The walls of the port adjacent the discharge opening are water-cooled by pipes 15. 85

The air uptakes 16 lead from slag pocket 17 and their upper ends open into air ports 17' and into supplemental passages 18 which latter lead to the furnace chamber 13. The ports 17' as shown lead into the combined 100

port 12 laterally of the water-cooled port 8. As shown in Figure 1, the ports 17' are of greater depth than the port 8. The passages 18 are controlled by vertically movable dampers 19 which move in water-cooled frames 20.

In the operation of my furnace, upon the incoming end the dampers 19 are lowered to close off the passages 18. The gas fuel 10 comes through slag pocket 7 and uptake 6 to the port 8 through which it is discharged into the combined port 12. The air comes through the slag pocket 17 and uptakes 16 and is led through ports 17' to the mixing 15 port 12. The dampers 19 effectively block off the passages 18.

It will be observed that the air streams impinge laterally upon the gas stream and since they are of greater height than the 20 gas stream, the gas will be completely surrounded by the air stream. The reduced mixing port 12 serves to adequately intermingle the gas and air and to properly direct the flame upon the bath of metal in the 25 furnace chamber 13.

Upon the outgoing end of the furnace, the dampers 19 are raised and the products of combustion pass out through passages 18 and through the port 12. The 30 passages 18 are greater in area than the port 12 and are also so designed as to more readily facilitate the discharge of the gases so that the greater portion thereof passes through these passages. The water-cooled port 8 is 35 thus subjected to the flow of only a minor portion of the gases. The greater portion of the flow which does impinge against the port 8 will be conducted through the port and down the uptake 6.

40 It is to be understood that suitable regenerative chambers may be connected to the slag pockets 7 and 17 and all other customary appurtenances of open hearth furnaces may be provided. Such apparatus 45 and constructions are old in the art and form no part of the present invention.

The particular design shown is to be taken as illustrative only and I reserve the right to make such modifications in design and 50 construction to meet varying conditions as come within the scope of the appended claims.

I claim:

1. In an open hearth furnace, a gas port, 55 air uptakes, air ports leading from said uptakes adjacent the gas port and adapted to discharge an air stream enclosing the gas stream, and supplemental passages connecting the air uptakes and the furnace chamber.

2. In an open hearth furnace, a water-cooled gas port, air uptakes, air ports leading from said uptakes adjacent the gas port, the air ports extending below the gas port, 60 and adapted to discharge an air stream en-

closing the gas stream, and supplemental passages connecting the air uptakes and the furnace chamber.

3. In an open hearth furnace, a gas port, laterally placed air ports opening toward the gas port, air passages leading to said ports and supplemental passages connecting the air passages with the furnace chamber. 70

4. In an open hearth furnace, a gas port, laterally placed air ports opening toward the gas port, said air ports extending below the gas port and adapted to discharge an air stream encircling the gas stream, air passages leading to said ports and supplemental 75 passages connecting the air passages with the furnace chamber. 80

5. In an open hearth furnace, a gas port, air uptakes, air ports leading from said uptakes adjacent the gas port and adapted to 85 discharge an air stream enclosing the gas stream, supplemental passages connecting the air uptakes and the furnace chamber, and a combined air and gas mixing port located between the air and gas ports and the furnace chamber. 90

6. In an open hearth furnace, a gas port, laterally placed air ports opening toward the gas port, said air ports extending below the gas port and adapted to discharge an air stream encircling the gas stream, air 95 passages leading to said ports, supplemental passages connecting the air passages with the furnace chamber, and a combined air and gas mixing port located between the air and gas ports and the furnace chamber. 100

7. In an open hearth furnace, a tubular, water-cooled gas port, air uptakes located laterally of the gas port, air ports leading from said uptakes adjacent the gas port, 105 said air ports extending below the gas port and adapted to discharge a stream of air encircling the gas stream, and supplemental passages connecting the air uptakes and the furnace chamber, and a combined air and gas mixing port located between the air and gas ports and the furnace chamber. 110

8. In an open hearth furnace, a gas port, air uptakes, air ports leading from said uptakes adjacent the gas port and adapted to 115 discharge an air stream enclosing the gas stream, and supplemental passages connecting the air uptakes and the furnace chamber, said passages being provided with means adapted to selectively interrupt flow 120 therethrough.

9. In an open hearth furnace, a tubular, water-cooled gas port, air uptakes located laterally of the gas port, air ports leading from said uptakes adjacent the gas port and 125 supplemental passages connecting the air uptakes and the furnace chamber, said passages being provided with dampers adapted to selectively interrupt flow therethrough.

10. A metallurgical furnace comprising a 130

hearth, a combined fuel and air port at each end of the furnace above the hearth and having a progressively constricted port area from the end of the furnace toward the hearth with an inclined floor to direct the fuel downwardly to impinge upon the metal on the hearth, and longitudinal side flues communicating with the furnace and with the opposite sides of the respective combined fuel and air ports.

10 Signed at Chicago, Illinois, this 1st day of April, 1922.
